(57) **CLAIM**

The ornamental design for a orthodontic archwire, as shown and described.

DESCRIPTION

FIG. 1 is a front perspective view of an orthodontic archwire according to a first embodiment of my new design with a circle profile;

FIG. 2 is a front view thereof;

FIG. 3 is a left side-right side view thereof;

FIG. 4 is a perspective view thereof;

FIG. 5 is a rear view thereof;

FIG. 6 is a top-bottom view thereof;

FIG. 7 is a front perspective view of an orthodontic archwire according to a second embodiment of my new design with a square profile;

FIG. 8 is a front view thereof;

FIG. 9 is a left side-right side view thereof;

FIG. 10 is a perspective view thereof;

FIG. 11 is a rear view thereof;

FIG. 12 is a top-bottom view thereof;

FIG. 13 is a front perspective view of an orthodontic archwire according to a third embodiment of my new design with a rectangular profile;

FIG. 14 is a front view thereof;

FIG. 15 is a left side-right side view thereof;

FIG. 16 is a perspective view thereof;

FIG. 17 is a rear view thereof; and,

FIG. 18 is a top-bottom view thereof.
